UNITED STATES PATENT OFFICE

1,940,750

WINDOW BALANCING MEANS

John Hellinga, Sr., Chicago, Ill.

Application November 8, 1932. Serial No. 641,785

2 Claims. (Cl. 16—201)

This invention relates to an improved window structure wherein the principal improvement and changes reside in the provision of a frame characterized by distinguishable sliding sash 5 guide strips and associated sliding sashes equipped with built-in rolling screens.

Briefly stated, an outstanding feature of the invention is predicated upon a sliding sash having an especially formed rail provided with a 10 rolling screen wherein the free end of the screen is anchored on the window frame and the opposite end wound on an especially developed winding and reeling roller, rack and pinion means being provided for positively rotating the roller in 15 order that the screen will automatically span the opening as the sash is moved to open position.

Another feature of the invention is predicated upon an automatically operable spring lift device for a sliding sash which device is built into 20 the sash and provided with positive locking means and a pinion for co-action with the same rack means which serves to actuate the screen roller pinion.

Those structural details which serve to explicitly distinguish the invention from similar 25 prior art devices will become more readily apparent from the following description and drawings.

In the accompanying illustrative drawings, 30 wherein like numerals are employed to designate like parts throughout the same:

Figure 1 is a front elevational view of the frame, sash, and screen arrangement as developed in accordance with the principles of the 35 present invention.

Figure 2 is a vertical section taken approximately on the plane of the line 2—2 of Figure 1.

Figures 3 and 4 are enlarged fragmentary detail sections on the lines 3—3 and 4—4 respectively of Figure 1.

Figure 5 is a detail sectional view illustrating the screen roller and its associated accessories or parts.

Figure 6 is a detail view of one of the end retaining plates.

Figure 7 is a cross section on the line 7—7 of Figure 5 showing only the roller.

Figure 8 is a view in section and elevation showing a fragmentary portion of the especially 50 recessed portions of the corner of one of the improved sashes.

Figure 9 is a horizontal section on the line 9—9 of Figure 2.

Figure 10 is a detail view of the parting strip.

Figure 11 is a section on the line 11—11 of 55 Figure 10.

Figure 12 is a view in section and elevation showing the sash equipped with one of the improved spring operating devices.

Figure 13 is a detail view of the device per se.

Figure 14 is a section on the line 14—14 of Figure 13.

Figure 15 is a detail view of the plate shown in Figures 12 and 13.

Figure 16 is an enlarged illustrative detail view 65 on the line 16—16 of Figure 12.

Attention is first invited to Figures 1 to 11 inclusive which figures are intended to specifically portray the screen arrangement. In Figure 1, the window frame is generally designated 70 by the numeral 17, the numeral 18 indicating the upper sliding sash and 19 the lower sliding sash. So far as the incorporation of the screens in these sashes is concerned, the construction is the same in each instance, therefore a description 75 of one sash will suffice for both.

Directing attention to Figures 3 and 4 for example, it will be observed that the especially fashioned rail 20 is formed with a longitudinal or horizontal bore 21 and a radial slot 22 for 80 the screen 23. The screen is attached at its inner end to a roller 24 confined in the bore 21. In this connection I call attention to a substantially L-shaped cornice or wear plate 25 having its edging flange formed with a coiled or rolled terminal 26 which constitutes a screen guiding bead extending into the feed slots 22 through which the screen is paid out and retracted in an obvious manner.

I also call attention to the numeral 27 which 85 designates a complemental wear plate which faces the rail 20 and which terminates in a laterally bent lip 28 co-operating with the bead in forming a practical slide way for the screen.

Attention is now called to Figure 5 which 90 shows the screen roller assembly. It will be noted that trunnion pins 29 are provided at opposite ends of the roller to protrude through bearing slots 30 in the attaching and retention plates 31. These plates as shown in Figure 6 are of general rectangular form and set into the adjacent recesses 32 (see Figure 8).

Obviously the trunnions 29 rotate in the slots and have the requisite vertical play necessary to permit effective coiling of the screen on the roller without binding. At the opposite end the trunnions 29 carry fixed pinions 33.

I now call attention to Figure 9, showing the vertical stop strips 34, 35 and 36 respectively which define the guideways for the sliding sashes in a conventional manner. In accordance with the present invention however the parting strip 35 and the adjacent guide strip 36 are serrated to form rack teeth 37 and 38 with which the pinions have positive operating engagement in an evident manner (see Figure 2). Thus, as the sashes are moved from closed to open position, the rack and pinion means serve to rotate the respective rollers for unwinding the screen, and as the sashes are moved to closed position 110

the reverse action takes place under which circumstances the screens are again rewound on the rollers. Therefore, by permanently anchoring the free ends of the screens to proper points on the window frame, and attaching the inner ends to the rollers 24, and through the instrumentality of the rack and pinion means, effective and automatic screen operation is accomplished.

Directing attention now to Figures 12 to 16 inclusive, I show a device which is closely associated with the screen arrangement and which functions primarily as a sash operator. As shown in Figure 12, the sash rail 39 is formed with a mortise 40 and an edge recess 41 to accommodate the closure operating device illustrated in Figure 13.

The device here shown comprises a bearing and attaching plate 42 located and fastened in the recess 41, together with a casing or cylinder 43. A bearing washer 44 is threaded into the right-hand end of the cylinder so that the washer co-operates with the plate 42 in providing bearings for the rotary shaft 45.

On the left hand end of the shaft is a rigid pinion 46 designed and located to co-operate with the rack teeth of the adjacent guide strip (not shown in these figures). The means for rotating the shaft and pinion or cogwheel comprises a coiled spring 47 having one end 48 attached to the shaft and the opposite end 49 attached to the relatively stationary plate 42.

Assuming that the device is on the lower sash, it is evident that when the sash is lowered the spring 47 is tensioned sufficiently to automatically elevate the sash when released. In order to retain the sash in a set position, a brake device is utilized, said device being sufficiently illustrated in Figure 16.

The brake device comprises a ring 50 which embraces the shaft and which has retaining teeth 51 to bind against the shaft to hold it against rotation. The ring is provided with a screw-threaded shank 52 tapped into a rotary bushing 53 rotatably mounted in a bearing plate 54 attached to the sash rail. The bushing is in turn rotated through the agency of a finger grip 55. By thus turning the finger grip 55 the elements 52 and 53 co-act to bind the ring 51 firmly against the shaft 45 to hold it against rotation

to counteract the influence of the spring 47 when the spring is under tension. Consequently the device constitutes an automatic sash operator.

It is thought from the foregoing description that the advantages and novel features of the invention will be readily apparent.

It is to be understood that changes may be made in the construction and in the combination and arrangement of the several parts provided that such changes fall within the scope of the appended claims.

I claim:

1. A sliding closure operator comprising a sliding sash provided in one of its rails with a plate recess and a casing mortise, an attaching plate located and fastened in said recess and provided with a bearing aperture, a cylindrical spring casing located in said mortise and provided with a bearing washer at one end thereof, a shaft mounted for rotation in the washer and bearing aperture, a pinion attached to the operating end of the shaft and adapted for co-operation with a guide strip having rack teeth, a coiled spring located in the casing and surrounding the shaft and attached at one end to the shaft and at its opposite end to said plate, and retaining means for said shaft.

2. A sliding closure operator comprising a sliding sash provided in one of its rails with a plate recess and a casing mortise, an attaching plate located and fastened in said recess and provided with a bearing aperture, a cylindrical spring casing located in said mortise and provided with a bearing washer at one end thereof, a shaft mounted for rotation in the washer and bearing aperture, a pinion attached to the operating end of the shaft and adapted for co-operation with a guide strip having rack teeth, a coiled spring located in the casing and surrounding the shaft and attached at one end to the shaft and at its opposite end to said plate, and retaining means for said shaft, said retaining means comprising a toothed ring embracing the shaft, a screw-threaded shank carried by said ring, a rotary bushing having a screw-threaded socket into which said shank is threaded, means for supporting the bushing, and means for turning the bushing.
